HINGE FOR DOORS OR WINDOWS

Filed Nov. 25, 1929

Inventor
William D. Ferris
By Arthur H. Durand, Atty.

UNITED STATES PATENT OFFICE

WILLIAM D. FERRIS, OF STERLING, ILLINOIS, ASSIGNOR TO FRANTZ MANUFACTURING CO., OF STERLING, ILLINOIS, A CORPORATION OF ILLINOIS

HINGE FOR DOORS OR WINDOWS

Application filed November 25, 1929. Serial No. 409,477.

This invention relates to doors or windows that are hinged to swing about an axis, usually a vertically disposed axis, and which in some cases are mounted to move up and down when in closed position.

Generally stated, the object of the invention is to provide a novel and improved construction and arrangement whereby a door or window hinge is provided with adjustable friction means for frictionally holding the door or window in an open or partially open position, so that the door or window will not blow around, and will not be liable to slam and break something when closed.

It is also an object to provide a novel and improved construction and arrangement whereby a door or window hinge is provided with a sliding connection, between the stationary and movable sections thereof, whereby the movable section and the door or window supported thereby may move up and down, which vertical displacement is necessary in the opening and closing of some doors or windows.

It is also an object to provide certain details and features of construction and combinations tending to increase the general efficiency and desirability of a window or door hinge of this particular character.

To the foregoing and other useful ends, the invention consists in matters hereinafter set forth and claimed and shown in the accompanying drawings, in which—

Fig. 1 is a front elevation of a door or window hinge embodying the principles of the invention, showing adjacent portions of the door or window and the frame, and showing certain portions of the hinge in vertical section;

Fig. 2 is a similar view, but does not show any of the parts in section, and in this view the door or window is in raised position;

Fig. 3 is a horizontal section on line 3—3 in Fig. 1 of the drawings; and

Fig. 4 is a vertical section on line 4—4 in Fig. 1 of the drawings.

As thus illustrated, the invention comprises an upper hinge section 1 provided with a bearing portion 2, and provided with a struck-out portion 3 forming a guide, this section of

the hinge being secured by screws 4 to the door or window 5, which latter may be of any suitable character. The lower section 6 of the hinge has a bearing portion 7, and a pin or pintle 8 is inserted through the bearing portions, as shown more clearly in Fig. 1 of the drawings. Said pin or pintle has a flange or shoulder 9 upon which the portion 2 is supported, when the door or window is in lowered position.

A flat piece 10 is interposed between the shoulder 9 and the fibre friction washer 11, this piece 10 having a notch 12 at its outer end for engagement with the guide 3, previously mentioned. A bracket piece 13 is interposed between the washer 11 and the upper end of the bearing portion 7, this piece 13 being secured to the window or door frame 14 by a screw 15, or other suitable means.

A metal washer 16 and a nut 17 and a lock-nut 18 are applied to the screw-threaded lower end portion of the pin or pintle 8, as shown, whereby the friction between the washer 11 and the flat surfaces of the metal pieces 10 and 13 may be regulated.

With this construction, the door or window 5 may be moved up and down, as the bearing portion 2 can slide up and down on the upper portion of the pin or pintle 8, and the guide 3 will move up and down in the notch 12, whereby the door or window can be lowered in its closed position, as is necessary with some doors or windows, in order to provide a more or less weather-tight joint at the lower edge of the door or window.

The pieces 10 and 13 provide broad friction surfaces, for engagement with the washer 11, and in this way the door or window can be held frictionally in open or partially open position, thus preventing the door from swinging around or being blown shut. At the same time, of course, the friction means do not interfere with the free movement of the bearing portion 2 on the upper portion of the pintle. By adjusting the nuts 17 and 18, the friction can be regulated to make the door or window open and close with the desired frictional resistance.

What I claim as my invention is:

1. A door or window hinge comprising

hinge leaves having knuckles, having friction means distinct from the hinge itself, interposed between the opposing ends of two knuckles of the hinge to frictionally hold the door or window in open or partially open position, without preventing the opening and closing thereof, and provided with adjusting means for regulating the friction, said friction means comprising a shoulder on the pindle, between said knuckles, including a swinging member and a stationary member engaging the opposite sides of said washer, between said knuckles, and said adjusting means comprising a nut screwed on the lower end portion of said pindle, thereby operative to vary the pressure on said washer.

2. A door or window hinge comprising hinge leaves having knuckles, having friction means distinct from the hinge itself, interposed between the opposing ends of two knuckles of the hinge to frictionally hold the door or window in open or partially open position, without preventing the opening and closing thereof, and provided with adjusting means for regulating the friction, said hinge having means to permit up and down movement of the door or window, without disturbing said friction means, permitting removal of the door or window without disturbing said pindle.

3. A door or window hinge comprising hinge leaves having knuckles, having friction means distinct from the hinge itself, interposed between the opposing ends of two knuckles of the hinge, to frictionally hold the door or window in open or partially open position, without preventing the opening and closing thereof, and provided with adjusting means for regulating the friction, said friction means comprising two plates between the knuckles, means for securing one plate to the door or window frame, one of said hinge leaves being rigid with the door or window and having means to detachably and slidably engage the other plate, a washer between said plates, and a shoulder on the pindle of the hinge, engaging said last-mentioned plate, said adjusting means being on one end of said pindle and serving to regulate the pressure of said shoulder on said plates and washer.

4. A door or window hinge comprising hinge leaves having knuckles, having friction means distinct from the hinge itself, interposed between the opposing ends of two knuckles of the hinge to frictionally hold the door or window in open or partially open position, without preventing the opening and closing thereof, and provided with adjusting means for regulating the friction, said friction means comprising two plates between the knuckles, means for securing one plate to the door or window frame, one of said hinge leaves being rigid with the door or window and having means to detachably and slidably engage the other plate, a washer between said

plates, and a shoulder on the pindle of the hinge, engaging said last-mentioned plate, said adjusting means being on one end of said pindle and serving to regulate the pressure of said shoulder on said plates and washer, and said shoulder forming a step bearing to support the knuckle that is rigid with said door or window.

Specification signed this 20th day of November, 1929.

WILLIAM D. FERRIS.
